DESIGN FOR A CIGARETTE LIGHTER

Dwight C. Jones, Whittier, Calif., assignor to Zephyr Manufacturing Co., Inglewood, Calif., a copartnership

Application July 9, 1945, Serial No. 120,575

Term of patent 3½ years

(Cl. D48—27)

To all whom it may concern:

Be it known that I, Dwight C. Jones, a citizen of the United States, residing at Los Angeles, in the county of Los Angeles and State of California, have invented a new, original, and ornamental Design for Cigarette Lighters, of which the following is a specification, reference being had to the accompanying drawing, forming a part thereof.

Fig. 1 is a perspective view of a cigarette lighter showing my new design;

Fig. 2 is a fragmentary perspective view similar to Fig. 1 but illustrating the cover in open position;

Fig. 3 is a perspective view of the cigarette lighter shown in Fig. 1, as viewed from the opposite side thereof; and

Fig. 4 is a bottom plan view of the cigarette lighter shown in Figs. 1, 2 and 3.

I claim:

The ornamental design for a cigarette lighter, as shown.

DWIGHT C. JONES.
